Primary Examiner — Cynthia Ramirez*Assistant Examiner* — Michael A Maharajh(74) *Attorney, Agent, or Firm* — Evan Feldstein**CLAIM**

I claim the ornamental design for a skin massager, as shown and described.

DESCRIPTION

FIG. 1 is a perspective view of a skin massager.
FIG. 2 is a front view of the skin massager.

FIG. 3 is a rear view of the skin massager.

FIG. 4 is a right side view of the skin massager.

FIG. 5 is a left side view of the skin massager.

FIG. 6 is a top view of the skin massager; and,

FIG. 7 is a bottom view of the skin massager.

The broken lines shown in the figures are for the purposes of illustrating portions of the skin massager, which form no part of the claimed design.
